UNITED STATES PATENT OFFICE

FRANK S. HARRELL, OF LOYALTON, CALIFORNIA

GRINDING MACHINE

Application filed October 27, 1926. Serial No. 144,541.

The present invention relates to improvements in boring machines, particularly in those used for boring or reboring or regrinding cylinders of engines.

5 The general object of my invention is to provide a boring machine, which can be secured to the cylinder, by the same bolts which are used to secure the cylinder head to the cylinder, thereby providing a boring 10 machine, which can be attached in place of a cylinder head in any position of the cylinder.

A further object of my invention is to provide a boring machine, which can be used 15 in cylinders of all diameters that occur in the every day practice.

The above and other objects are accomplished by instrumentalities pointed out in the following specification.

20 The invention is clearly defined in the claim.

A satisfactory embodiment of the invention is illustrated in the accompanying drawing, forming a part of the specification and 25 in which :

Figure 1 is a side elevation of the invention in use,

Figure 2 is a top plan view of the invention,

30 Figure 3 is a detail of the supporting plate of my device,

Figure 4 is a cross section taken on Figure 3 line 4—4,

35 Figure 5 is a perspective view of one of the standards of my device,

Figure 6 is a fractional section of my device showing its attachment to an electric motor,

40 Figure 7 is a sectional detail on the line 7—7 of Figure 6,

Figure 8 is a detail of my adjustable boring and grinding tool,

Figure 9 is a perspective view of a disc of my grinding tool,

45 Figure 10 is a cross section taken on line 10—10, on Figure 8, and

Figure 11 is a modified adaptation of my invention.

In the drawing 15 indicates a cylinder of 50 any type of reciprocating engine; 16 is the

bore of the cylinder, which is bored or ground by the boring device 17. The standards 18 are preferably Z shaped as shown clearly in Figure 5, one end of each standard having a hole 19 for receiving the bolts 20 which will 55 secure the standards 19 to the cylinder 15. In the other end of standards 18 is an elongated aperture 21, through which the bolts 22 secure the standards 18 to the plate 23. Plate 23 is fixedly secured to the casing of 60 an electric motor 24 by screws 25.

The hollow shaft 26 of the motor 24 is secured by any conventional means to the rotor of the electric motor, and is supported in ball bearings 27 as shown in Figure 6. A solid 65 shaft 28 is slidable in the hollow shaft 26, and rotated with the hollow shaft 26 by means of keys 29 as shown in Figure 7.

The casing 30 of the motor is threaded at 31, a screw 32 is extended through the threaded hole 31 into the solid shaft. The screw 32 has a ball shaped end 33. A socket 34 is secured to the end of the solid shaft 28 by means of screws 35. The ball 33 and socket 34 form a ball and socket joint, thereby permitting the screw to be rotated and advanced without rotating the shaft 28.

A handle 36 is secured to the other end of the screw 32, for turning the screw 32.

A boring or grinding tool 37 is attached to 80 the shaft 28, and is held in place by a set screw 39. The end of the shaft 28 is square and is secured into the square hole 40 of the frame 38. Plates 41 and 42 are integral parts of frame 38. Each of the plates 41 extends 85 parallel with a plate 42, thereby forming two receptacles for the carborundum discs 43. The discs 43 are secured between the plates 41 and 42 by means of bolts 44. An elongated aperture 45 of the discs 43 permits the lateral adjustment of the discs.

Two bearings 46 are extended from the frame, at right angles to the plates 41 and 42, and support threaded rods 47, the rods 47 95 having a lefthand screw at one end as at 48, and a righthand screw at the other end as at 49. The screws 48 and 49 are secured in the threaded wall of the holes 50 of the discs 43.

Adjusting wheels 51 are fixedly secured on 100

rods 47, at about the center, between the forks of the bearings 46.

My invention operates as follows:

Bolts 22 can be placed through the elongated aperture 21, thereby the device can be secured in place on the cylinder head, by the standard bolts.

The rotating motor will rotate the solid shaft 28 and the cutting tool 37. To advance the cutting tool into the cylinder bore 16, the operator turns the handle 36, thereby advancing screw 32, which in turn advances the solid shaft 28 in the hollow shaft 26.

The ball 33 and socket 34 joint prevents the advancing screw to interfere with the rotation of the cutting tool.

The adjustment of the cutting tool to different bore diameters can be effected by loosening the bolts 44 then turning the adjusting wheels 51, the wheels turn the screws 47 and 48 in the holes 50, thereby moving the carborundum discs 43 toward or away from the center, making the boring diameter smaller or larger respectively. Then by tightening up the bolts 44, the tool is fixed in the desired position.

A chuck 52 for receiving a drill bit 53 may be secured in place of the boring or grinding tool.

30 A device is shown in use as a drilling machine in Figure 11.

Although I have shown and described one embodiment of my invention, it is to be understood that the same is susceptible of various changes and I reserve the right to employ such as may come within the scope of the appended claim.

I claim:

40 A grinding machine comprising a support, a motor carried thereby, a hollow shaft rotated by said motor, a solid shaft slidable in said hollow shaft and turnable therewith, a tool carried by said solid shaft, means for advancing said solid shaft while it is rotating, 45 said means including a manually actuated screw and a ball bearing disposed between the end of said screw and said solid shaft, and means for adjusting the longitudinal axis of said solid shaft laterally with respect to said support.

FRANK S. HARRELL.
